UNITED STATES PATENT OFFICE.

JOHN T. SCHAAFF, OF WASHINGTON, DISTRICT OF COLUMBIA.

VERIFYING MACHINE.

1,426,223.

Specification of Letters Patent. Patented Aug. 15, 1922.

Application filed August 12, 1921. Serial No. 491,725.

To all whom it may concern:

Be it known that I, JOHN T. SCHAAFF, a citizen of the United States, residing at Washington, District of Columbia, have invented certain new and useful Improvements in Verifying Machines, of which the following is a description, reference being had to the accompanying drawing and to the figures of reference marked thereon.

The invention relates to new and useful improvements in punches for punching holes or verifying punched holes in cards adapted to be used in tabulating machines.

An object of the invention is to provide a machine of the above type with means whereby a card may be shifted on the carrier therefor for the purpose of registration and with yielding means for dressing the cards against the registration means.

A further object of the invention is to provide a machine of the above type with locking means for the key lever so that only one key lever can be depressed at a time.

A further object of the invention is to provide the traveling carrier for the card with a hesitation mechanism whereby one or more holes may be punched or verified in a single column before feed of the carrier takes place.

A still further object of the invention is to provide a skip mechanism wherein the skip lifter may be readily removed from the machine when worn and another substituted therefor.

A still further object of the invention is to provide a mechanism which insures the withdrawing of the skip lifter by the idle movement of the carrier, provided said skip lifter is thrown into operative position by the skip key when the carrier is released by the skip key after the card has been completely punched or verified.

A still further object of the invention is to provide a releasing key which releases not only the escapement for the carrier but also the hesitation pawl so as to permit free unrestrained movement of the carrier.

A still further object of the invention is to provide a punching machine for verifying punched holes in cards wherein when the punch is depressed at the last column in the card, a step movement of the carrier may take place, thus indicating that the last hole

in the card has been properly punched.

A still further object of the invention is to provide a marginal stop which is independent of the rack bar for controlling the feed of the carrier, which marginal stop may be adjusted throughout a wide range so that holes may be punched or verified in the last column only, if desired, of a card, and also to locate said marginal stop so that it is entirely out of the way of the operator.

A still further object of the invention is to provide a cover plate independent of the track on which the rollers to the carrier run for holding the rollers on the track, said cover plate being readily detachable and simple in construction so that it may be cheaply made.

These and other objects will in part be obvious and will in part be hereinafter more fully disclosed.

In the drawings which show by way of illustration one embodiment of the invention:

Figure 1 is a plan view of a machine embodying my improvements;

Fig. 2 is a side view of the same;

Fig. 3 is an enlarged view partly in plan and partly in section with the key levers and punches controlled thereby and also the upper part of the frame removed;

Fig. 4 is a view from the rear of the machine showing in side elevation a portion of the machine, and particularly the hesitation pawl and operating mechanism therefor;

Fig. 5 is a perspective view showing the escapement mechanism, the bail for operating the same, the hesitation bar, the rack bar, and the hesitation mechanism; also the adjustable means for shifting the card on the carrier for registration;

Fig. 6 is a view in vertical section transversely through a portion of the machine showing the carrier in end view;

Fig. 7 is a detail in side elevation showing a part of the rack bar, the driving ratchet gear therefor and the operating mechanism for the ratchet gear;

Fig. 8 is a perspective view with the parts separated showing a portion of the skip mechanism, the retractor mechanism, and the shiftable means for the card;

Fig. 12 is a view partly in side elevation and partly in section of the mechanism 15 shown in Fig. 11;

Fig. 13 is an enlarged sectional view through one of the projecting arms of the carrier and showing the yielding dressing device for the cards;

Fig. 14 is a perspective view of one of the marginal stops and showing in dotted lines a portion of the rack bar associated therewith;

Fig. 15 is a perspective view showing a modified form of the marginal stop;

Fig. 16 is a side view showing a modified form of means for supporting the escapement pawl for the carrier whereby the same may be adjusted, and it is also yieldingly 30 mounted;

Fig. 17 is a view showing the portion of the indicator for indicating the position of the card to be punched or verified and also showing in side elevation the skip bar and the relation of the notches therein to the several fields in the card, and

Fig. 18 is a detail view showing the connection of the hesitation feed pawl to its lever.

The invention is directed to a punch which from certain of its aspects is especially adapted for verifying the punched holes in a card adapted to be used in a tabulating machine, while from certain other aspects

of the invention, said punch may be used for punching the holes in a card which is adapted to be used in a tabulating machine. For the sake of description, I have referred to the machine as a punching machine with the understanding that this term imposes no limitations whatever upon the inventions described and set forth in the claims. I have illustrated the invention as embodied in a machine for verifying the punched holes in a card, and the inventions will be described in connection with this illustrated embodiment of the invention.

The invention consists of a base plate along which a carrier moves, and supported by said base plate is a series of key levers controlling a series of punches. Each punch is associated with a die, and the card passes over a die and the key lever is adapted to bring the punch down into contact with the card or to cause the punch to pass

through the hole in the card if a hole has already been punched therein. When the punch passes through the hole in the card, the bail of the escapement mechanism is depressed so as to feed the carrier forward, which forward movement of the carrier indicates to the operator that the card has been properly punched. Associated with the carrier is adjustable means for supporting the end of the card, which is utilized in positioning the card in a tabulating machine so that the punches may be brought into proper registration with the field to be punched in the card, or so that the punches may be brought into proper registration with prior punched holes in the card. The carrier is also provided with yielding means for holding the card against the shiftable means for the card so as to insure that the card is always dressed from the same end thereof regardless of slight variations in the lengths of the cards. The carrier is moved by means of a spring operated mechanism and is controlled by an escapement mechanism which is of the usual character. The bail of the escapement mechanism is depressed by a key lever provided there is a hole punched in the card. These key levers are mounted on yielding fulcrums and if there is no hole in the card, then the fulcrum yields so that the key lever is not depressed sufficiently to actuate the bail of the escapement mechanism. A skip mechanism including a skip lifter is also provided, which may be used if desired, in connection with a skip bar properly formed so that the operator may skip from one field to another predetermined field without stepping the carrier through all the successive steps between the fields. This skip lifter is automatically retracted by the retracting mechanism when the carrier is moved to its initial position, that is, for positioning the card for the beginning of the punching or verifying operations. This retracting mechanism operates at the beginning of the movement of the carrier so as to prevent the skip lifter from riding on the edge of the skip bar as the carrier is moved to the right. A hesitation mechanism is also provided which is so constructed that a series of holes may be punched in the same vertical column or a series of holes may be verified in the same vertical column before the carrier is stepped forward, and means is also provided for locking the pawl of the hesitation mechanism out of operation when desired. A releasing mechanism is also provided for releasing the escapement of the carrier and also for releasing the hesitation pawl so that the carrier may be quickly moved to a position where the card may be taken therefrom. Means is also provided for permitting the carrier to move forward when the punch has operated for

punching or for verifying the punched hole in the last column of the card, and this mechanism is preferably so constructed as to permit the movement of the card to a position entirely out from underneath the die for the easy and quick release of the card and the insertion of a new card in its place. There are other more or less minor features of the invention which will appear from the detailed description of the mechanism which will now be given.

My improved machine consists of a base or bed plate 1 mounted on supporting legs 2, 2. Overlying the base plate is an upper frame 15 work 3 which includes guide plates 4 and 5 for a series of keys 6 which are indicated in Figures 1, 2 and 9 of the drawings. Associated with each key is a key lever 7. This key lever 7 is fulcrumed at its rear end on a pin 8 which extends up into a housing 9 carried by the upper frame portion 3 of the machine. A spring 10 (see Fig. 9) located in the housing bears against a collar 11 on the fulcrum pin 8, and normally 20 presses said pin in a downward direction.

Associated with each key lever is a punch 12. This punch 12 as shown in the drawings, has a reduced end 13 smaller than the opening in the die which is indicated at 14 (see Fig. 9). The punch is primarily intended for verifying purposes, and the end of the punch is reduced so as to facilitate its easy passage through the punched hole in the card. The cards to be punched or verified are indicated at C in the drawings. The card passes between the die 14 and the stripper bar 15. It is understood, of course, that there are a series of punches and a series of key levers, one for each punch. The die 40 14 is shown in plan view in Fig. 3, and there is one punch for each opening in the die and therefore, it will be apparent that the punches are arranged in a line extending transversely of the machine. The punch is 45 raised by means of a spring 16 which bears at its lower end on the stripper bar 15 and at its upper end against a shoulder in the punch. When a key is depressed, the lever 7 swinging on the fulcrum pin 8 will depress 50 the punch. The spring 10 of the fulcrum pin is of greater tension than the spring for the punch. If the card has a hole therethrough in alignment with a punch, the punch will pass through the hole and the key lever 7 will move to its normal extreme 55 lower position. If, however, there is no hole in the card underneath the punch, when the punch strikes the card its downward movement will be stopped and the fulcrum pin 8 for the key lever will move upwardly. The tension on the spring 10 is so adjusted as to cause this action to take place. Directly underneath the key levers, is the swinging 60 bail 17 of the escapement mechanism. It will readily be seen that when the key lever

is depressed to its full movement, the swinging bail 17 will be moved downwardly and will cause the carrier to be stepped forward one step. If, however, the key lever does not move downward to any appreciable extent due to the fact that no hole has been punched in the card and the fulcrum pin 8 moves upwardly, then the bail 17 will not be depressed sufficiently to release the escapement mechanism. In verifying the 75 cards, the operator, of course, reads the original record and operates the keys just as though the card were to be punched. If there is a hole properly punched in the card, the bail will be depressed and the carrier 80 will move forward just as though a hole was being punched, and the operator knows that the hole is correctly punched. If, however, a key lever is not depressed by reason of the fact that there is no hole beneath the punch, 85 then there is no forward movement of the carrier, and the operator knows that the card in the machine has been incorrectly punched.

The key levers are interlocked so that only 90 one key lever can be depressed at a time. This is accomplished by providing a tube 18 which is preferably rectangular in cross section, and in which are formed a series of slots 19, 19 in the top, side and bottom of 95 the tube and in alignment with each other. Located within the tube are a series of balls 20. The ends of the tube are closed by end blocks 21. This tube is carried by the lower plate 5 beneath the key lever 7 and is held 100 thereon by suitable brackets 22 (see Fig. 9) and 23 (see Fig. 11). Each key lever has a depending locking blade 24. These blades as clearly shown in Fig. 10 are in alignment 105 with the slots 19. The balls are so proportioned that when a key lever is forced downwardly by depressing a key, the locking blade 24 moving between two adjacent balls will crowd the other balls endwise of the tube and the tube will be completely filled so that no 110 further sidewise or endwise movement of the balls can take place in the tube. In Fig. 10, the key lever 7^a is shown as depressed and the blade 24 has passed through the upper slot 19 and in between two adjacent balls. 115 The end balls are now against the end blocks 21 and no further movement can take place of the balls as above noted. If the levers 7^b should now be depressed, it would merely come in contact with the balls in the tube 120 and could not pass between the balls as the balls cannot move to permit the blade to get between them. It will therefore be seen that when one key is depressed, no other key can be depressed to a sufficient extent to bring 125 about any operation until the first key depressed has been released and raised to its normal position.

The cards are moved between the die and the stripper bar by means of a carrier which 130

consists of a rack bar 25 having laterally extending arms 26 and 27. Pivotally carried by the rack bar are rollers 28 and 29. These rollers are grooved to run on a track 5 30. Also carried by the arm 26 is a roller 31 (see Fig. 6). The roller 31 runs on the base plate of the machine. These three rollers support the carrier and permit the carrier to be freely moved back and forth 10 on the base plate of the machine. The rollers 28 and 29 are held on the track bar 30 by means of a cover plate 32. Said cover plate 32 is detachably secured to the track bar by means of screws 33. The cover 15 plate is bent outwardly as at 38^a and thence inwardly as at 34 so as to overlie the rounded heads 35 of the pivots for the rollers 28 and 29. This cover plate can be made of steel bars by rolling or drawing and cut in suitable lengths and forms a very simple and 20 cheaply made structure for holding the carrier in place on the machine.

The arm 27 at the right-hand end of the machine projects over the base plate and is 25 provided with supporting arms 36, 36 each of which has a horizontal groove 37 (see Fig. 8) therein adapted to receive the end edge of the card. These arms extend in 30 part into a recess 38 in the base of the machine. The arms 36 are adjustably secured to the arm 27 by means of screws 39, 39 which pass through slots 40, 40 in the arm 27. The other end of the card is adapted 35 to be engaged by a spring member 41 (see Fig. 13). Mounted on the arm 26 is a finger piece 42 by which the carrier may be readily moved to the right as viewed in Fig. 3 when the card is positioned for the beginning of the punching or verifying operation. Adjustably secured to the arm 26 40 is a bracket 43. Said bracket has a slot through which a screw 44 passes. The spring 41 is carried by this bracket. The bracket is slotted at 44' so that spring 41 45 extends therethrough and lies in front of the bracket. A card is placed in the groove 37 in the arm 36 at one end and the other end of the card is placed against the spring 41. This provides a yielding means for dressing 50 the card so as to insure that it will be held against the bottoms of the grooves 37 and thus properly registered if the arms 36, 36 are in turn in proper position for bringing about registration. In other words, if the 55 cards vary slightly in length, the springs will always dress a card to the right as viewed in Fig. 3.

In order to insure that a card is properly registered so that if holes are being punched, these holes will be suitably positioned for 60 operation in a tabulating machine, or if the cards have been punched and are being verified, that the punches will be positioned so as to pass through the punched holes, I have 65 provided the base of the machine with a

registering notch or mark 45, Fig. 1. This notch in the base plate of the machine is so positioned that if the end of the card is in alignment therewith, it will be properly registered for operation thereupon. The 70 adjustable arms 36, 36 may be readily shifted in the manner above described for bringing about this registration.

The position of the carrier for the card is readily indicated to the operator by means 75 of a traveling pointer 46 which is connected, by a suitable cord running over rollers, to the carrier. This pointer travels on a guide bar 47. Associated with the pointer is an 80 indicating card 48 which is a duplicate in part of the card being punched or verified so that the operator may readily determine from the position of the pointer the particular part of the card that is directly beneath the punches in the machine. Attention 85 is called to the fact that this indicator, together with the pointer therefor, is located in the plane or below the plane of the traveling arms of the carrier, and is thus out of 90 the way of the operator.

Marginal stops are provided for stopping the position of the carrier at any desired 95 field. For example, it often happens in the punching of a card that considerable data is written on the card and only the last few columns are punched. Sometimes only the last column, and these marginal stops are for the purpose of positioning the carrier quickly so that the first field to be punched or to be verified will be brought into 100 operative position relative to the punches. My improved marginal stop mechanism consists of a rack bar 49. This rack bar is suitably secured to the bed or base plate of the machine, and as clearly shown in Fig. 6, said rack bar is located at some distance beneath the upper surface of the base plate of the machine and is well out of the way. One form of my marginal 105 stop is shown in Fig. 14 and consists of a shouldered member 50 which is provided with teeth 51 on its under face corresponding to the teeth on the rack bar. Said shouldered member is placed on the rack bar in proper position so that the blocks 52 mounted on the arm 26 of the carrier will strike the faces 53 of said shouldered block and stop the movements of the carrier. In Fig. 14 of the drawings, the carrier when moved to position to engage the 110 marginal stop, is moving in the direction of the arrow. The shouldered member 50 is held in locked position on the rack bar by means of the stirrup 54. Said stirrup 115 is adapted to slide along the rack bar and slide over the portion 55 of the shouldered member and thus hold the teeth 51 in locked engagement with the teeth of the rack bar 49. A plate 56 is secured to the shouldered member and this plate is provided with a 120

125 130

notch 57 adapted to be engaged by a latch 58 so as to lock the stirrup in this position over a portion 55 of the shouldered member 50. Said latch is swung into locked position by means of a spring 59.

In Fig. 15 I have shown a slightly modified form of marginal stop. The stop in this figure is in the form of a bar 60 provided with teeth 61 which engage the teeth 10 of the rack bar 49. The plate 62 is for the purpose of readily handling the stop. After the stop has been placed on the rack bar, the stirrup 54 is slid over the portion 63 thereof and locks the same on the rack 15 bar. The stop 52 on the carrier strikes the end 64 of this marginal stop. The plates 56 and 62 are provided with openings 65. On the under side of the machine there is a threaded screw 66 (see Fig. 9) which 20 is adapted to pass through the opening 65 in one of these plates and this serves as a means for securing the marginal stop not in use to the machine so that it will not be lost.

The carrier is driven by a spring operated ratchet gear 66, which gear meshes with a ratchet gear 67 in the under face of the main rack bar 25 which controls the movements of the carrier. Said rack bar 25 is provided 30 with a series of teeth 69 with which the usual escapement cooperates. This ratchet gear 66 is carried by a plate 70. The gear is mounted on a pivot pin 71 and is keyed thereon. A spring 72 encircles the pivot of 35 the gear and is connected at one end to the gear and at its other end to a pin 73 carried by the plate 70. Plate 70 is secured to the frame of the machine by means of two screws 74 and 75. The screw 75 may be 40 removed and the plate dropped to the dotted line position in Fig. 7, which will cause the ratchet gear 66 to be unmeshed from the gear teeth 67 in the rack bar 25. The ratchet gear can then be rotated by the 45 operator to change the tension on the spring after which the plate 70 may be quickly raised to bring the ratchet gear into mesh with the gear on the rack bar and the screw 75 inserted to hold the plate with these 50 parts in proper engagement. This provides a very simple means for changing the tension on the operating spring for the carrier. 75^a is a limiting pin for plate 70.

The escapement mechanism for the carrier 55 is in the main, of the usual type, and only general reference to the structure thereof is thought necessary. The swinging bail 17 is pivotally carried by a shaft 76. Also mounted on this shaft 76 is a swinging member 77. The bail is provided with an adjustable screw 78 which is adapted to bear on a projecting portion of the swinging member 77. A spring 79 underneath the projecting 60 portion of the swinging member 77 normally 65 raises said member or turns the same in a

counter clockwise direction as viewed in Fig. 5. Mounted on the swinging member 77 is a pin 80. While I have shown in Fig. 16 an improved form of mounting of the escapement pawl, so far as its action by the escapement mechanism is concerned, it is of the usual construction. The escapement pawl is indicated at 81, and is provided with an opening 82 through which the pin 80 extends. When the pin 80 is raised, the pawl 81 is 70 raised. When the bail 17 is depressed, the screw 78 engaging the projection of the swinging member 77 will turn said swinging member in a clockwise direction about the shaft 76, raise the pin 80 and thus lift the 75 escapement pawl 81. Also carried by the swinging member 77 is an adjustable screw 83. This screw 83 extending down through the member, bears on the arm 84 carried by the swinging member 85. Said swinging 80 member 85 is moved in a clockwise direction around the shaft 76 by a spring 86 when released by the swinging movements of the block 77. The swinging member 85 is provided with a pin 87 which is adapted to engage in a notch 88 in the holding dog 89 of the escapement mechanism. Therefore, when the escapement pawl 81 is raised by the swinging of the bail 17, the holding pawl 89 is dropped. This escapement operates in 90 the usual way. When the holding dog engages the rack bar before the escapement pawl releases the same, and when the holding dog releases the rack bar, then the carrier jumps forward through the action of the 95 spring thereon.

In the form of the invention shown in Fig. 16, I have provided means for yieldingly mounting the escapement pawl 81. The shaft 76 in this form of the invention is 100 mounted at its forward end in a block 90. Said block 90 is pivoted at 91 to the bearing plate 92. Said block is formed with an upper flat surface 93 and an overhanging ledge 94. A bar spring 95 lies along said flat surface and underneath the ledge as clearly 105 shown in Fig. 16. The other end of this bar spring 95 extends beneath a lug 96 carried by the plate 92 and an adjusting screw 97 bearing on the spring, serves as a means for 110 increasing the tension of the spring. This spring bar 95 tends to turn the block 90 in a clockwise direction about its pivotal support and a stop screw 98 limits its movement. This stop screw is carried by a supporting 115 plate 92 and is adjustable and may be locked in adjusted positions.

By shifting the stop screw 98, the position of the escapement pawl 81 may be varied to take up wear between the parts. 120 Furthermore, when the carrier jumps through the action of the propelling spring thereon, the teeth of the rack bar strike the end of the escapement pawl, and this stops 125 the movement of the carrier. It will be 130

noted that the escapement pawl is yieldingly mounted, and therefore this action is cushioned. This greatly reduces the wear and peening effect on the escapement pawl.

- 5 I have referred to this mounting of the escapement pawl as a modification of the invention for the reason that although this yielding mounting of the pawl is rapidly adaptable to the hesitation mechanism about 10 to be described, I have not shown in the illustrated embodiment of the invention the yielding mounting of the pawl in connection with the hesitation mechanism.

It is often desirable to punch in a card a series of holes in the same vertical column, and of course, if a series of holes are punched in the card in the same vertical column, then it is necessary to verify the punching of these holes. I have provided a mechanism whereby a series of keys one after the other may be operated for punching holes in the same vertical column without any feed of the carrier and after the record feed takes place. The same operation also takes place 25 in connection with the verifying of punched holes. This hesitation mechanism consists of a bar 99 which is secured to the rack bar 25. Said bar 99 is provided with notches 100, 101 and 102 as shown in Fig. 5 of the drawings. These notches are of different depths and are located so as to correspond with the vertical column in which the series of holes is to be punched. Cooperating with this bar 99 of the hesitation mechanism is 35 a pawl 103. This pawl 103 is fulcrumed on one end of the escapement shaft 76 which is journaled in plate 105. The pawl is provided with an elongated slot 106 through which the shaft 76 extends. The rear end 40 of the pawl is provided with a segment rack 107. Cooperating with the segment rack is a feed pawl 108 and a locking dog 109. The locking dog 109 is pivoted at 110 to a bracket 111 and a spring 112 normally operates to 45 move the pawl toward the rack. The forward movement of the pawl is limited by a pin 113 (see Fig. 4). The feed pawl 108 is provided with a ball 114 at its upper end which fits in a socket in the lever 115 so 50 that the pawl is supported by the lever and at the same time is free to swing on the lever. A spring 116 normally moves the pawl toward the segment rack 107 and the pin 113 limits the forward movement of this pawl. 55 The lever 115 is pivoted at 117 to the plate 105. A link 118 is pivoted at 119 to the lever 115. The lower end of this link is pivotally connected to a pin 120 carried by the swinging member 85. The spring 86 is also 60 connected to this pin 120. A spring 121 is connected to a projecting lug 122 on the pawl 103 and to a pin on the plate 105. This spring normally pulls the pawl when free, to the position shown in Fig. 4. In this position, the segment rack is moved out of

range of the feed pawl 108 and the locking dog 109.

The pawl 103 runs along the top of the bar 99 and when the carrier reaches the position that the pawl is over one of the notches 70 in the bar 99, then the pawl drops into the notch. When the pawl drops into the notch, then the lifting of the escapement to release the carrier merely lets the carrier move until the end of the pawl 103 comes against the side 75 wall of the notch and the pawl is moved rearwardly on the escapement shaft 76 to the limit of its movement. The pawl 103 now holds the carrier from movement against the action of the motor spring. When the 80 key is depressed for punching the hole in the card, it depresses the bail in the usual way. The downward movement of the bail through the devices above referred to permits the actuation of the swinging member 85 and the raising of the pin 120. The upward movement of the pin 120 through link 118, swings the lever 115 and causes the feed pawl 108 cooperating with the segment rack 107 to move the rear end of the pawl 90 103 downward one tooth and the locking dog 109 will hold the pawl in this position. The depression of another key for punching or verifying a punched hole in a card again depresses the bail 17 and raises the pawl 95 103 another step. It will readily be seen that the number of holes punched or number of holes verified before the normal feed of the carrier again takes place depends upon the depth of the notches 100, 101 and 102. The 100 bar 99, of course, is shaped so as to correspond with the desired number of holes to be punched or verified in a given column.

In order that this hesitation mechanism may be rendered ineffective at the will of 105 the operator, I have provided a latch 123 (Fig. 12) pivoted at 124 to the cover plate 125 which it attached to the supporting plate 105 for the hesitation mechanism. This latch 123 is provided with a hook end 110 126. Projecting from the hesitation pawl 103 is a pin 127 which extends through an opening 128 in the cover plate and moves up and down therein. The operator may render the hesitation pawl inoperative by holding the release key in depressed position until the latch 123 is depressed and hook 126 is brought into engagement with pin 127. A stop pin 129 limits the swinging movement of the hesitation pawl 103 through the action of the spring 121 when the bar 99 is removed from the machine.

My improved punch is provided with a skip mechanism which in many of its details, is of the well known construction. I 125 have, however, provided a novel means of mounting the skip lifter whereby it may be readily removed and a new skip lifter substituted therefor. The skipping mechanism comprises a skip bar 130 which is 130

provided with a series of notches 131 located at the fields where the carrier is to stop for punching the punching operation. The skip lifter is indicated at 132 (see Figures 3 and 8). This skip lifter is provided with a hole 133 at its inner end adapted to take over a pin 134 and rest on a collar 135 secured to the pin. This pin 134 extends through a hole 136 in a toggle link 137 and into a T-bar 138. The pin is riveted in the T-bar. A pin 139 extends through a hole 140 in the other end of the toggle link 137. The pin 139 is first inserted in the upper bearing by a leaf spring 141, then through the toggle link and then into the lower bearing of said leaf spring. This leaf spring 141 is secured to the frame of the machine 15 by means of a screw 142, and a pin 143. The T-lever is provided with a slot 144 which engages over a pin 145. The leaf spring pressing on the toggle link tends to buckle the toggle one way or the other and the stop pin 146 engages one wall of the slot 144 or the other and limits the movement of the toggle lever. It will readily be seen that the skip lifter 132 will therefore be held in its retracted position where it is inoperative to in any way effect the regular escapement feed of the carrier, or held in its extended position where it becomes effective to modify the action of the escapement. The end of the skip lifter is held on the pin 134 by a plate 147. This plate 147 slides on a portion of the main frame between two stop pins 148, 148 and is held advanced over the skip lifter by means of a screw 149. By backing out the screw 149 the plate may be retracted so that its forward movement uncovers the inner end of the skip lifter, and the skip lifter can then be readily lifted off from the pin 134 and thus removed from the machine without in any way disturbing the pivotal support for the toggle link and T-lever. The plate 147 is provided with shoulders which engage the pins 148 to limit its retracted movement. The extreme forward end of the plate is provided with a socket 150 which is so shaped as to become a panel socket for the inner end of the skip lifter when the plate is retracted. When it is desired to insert a new skip lifter, the inner end is placed in the socket, which alines the hole in the skip lifter with the pin 134 and thus it may be readily positioned on the pin. The plate 147 is then forced inwardly covering the pin 134 and holding the skip lifter thereon.

It often occurs in the operation of the machine that the operator will operate the skip key as the last operation in the punching or verifying of a card. This leaves the skip lifter extended forwardly, and during the movement of the carrier toward normal position for punching or verifying a card, the skip lifter would slide along the rack bar causing a great wear on the skip lifter. I have provided means for automatically retracting the skip lifter on the first movement of the carrier toward normal position for the punching or verifying operation. This automatic skip lifter retractor consists of a pivoted arm 151. Said arm is pivoted at 152 to the frame of the machine and is provided with a pin 153 which projects between the arms 154, 154. The arms 154, 154 are drawn toward each other by a spring 155. These arms are pivoted respectively at 156, 156. There is a stop pin 157 between the arms and limiting pins 158, 158 outside of the arms. It will readily be seen that if the arm 151 is turned in one direction, the spring controlled arm 154 will be engaged by the pin 153 and yieldingly control the arm 151, while if it is moved in the other direction, the other arm 154 engages the pin 153 and yieldingly controls the arm 151, so that the arm 151 is normally held in an intermediate position, but is placed under tension when moved in either direction from said central position. Mounted on the carrier is a pin 159. This pin 159 is adapted to engage the inclined ledge 160 at the outer end of the arm 151. When the carrier moves to the left during the successive punching or verifying operations, or when finally released by the skip key, and moved to its extreme left-hand position, the pin 159 engaging the ledge 160 will swing the arm 151 so that it may pass said ledge and the arm 151 will then return to its normal position. On the first part of the movement of the carrier to the right, to bring the card to initial position for punching or verifying the pin 159 will strike the outer face of the ledge 160 and swing the arm 151 so as to cause the shoulder 161 to engage the end of the T-bar and retract the skip lifter. The skip lifter is thrown into operative position by an X-key (see Fig. 1). This X-key when depressed, engages the upwardly projecting arm 162 carried by a yoke 163. Said yoke has a downwardly projecting arm 164 which engages a laterally projecting arm 165 of the T-lever 138. This swings the T-lever so as to project the skip lifter forward, bringing shoulder 104 into one of the notches 131. The skip lifter stands normally under the escapement pawl of the escapement mechanism and when upon the movement of the carrier, shoulder 104 rides out of one of the notches 131 on the upper edge of the bar, it holds the escapement pawl out of engagement with the rack so that the carrier moves forward until the skip lifter drops into another notch. The skip lifter is retracted upon the depressing of any of the numeral 125 keys by means of lug 166 of bail 17, and this lug 166 engages an arm 167 of the key lever 138. When the yoke 163 is swung by the skip lifter key, an arm 168 carried thereby engages an adjustable screw 169 carried by 130

the swinging member 77 and raises the same, and through spring 86 swings rocking member 85 on its pivot 76. This releases the escapement pawl of the escapement mechanism and brings about the forward feed of the carrier and the action of the skip lifter on the escapement pawl as soon as the carrier moves the skip lifter out of the notch in the skip lifter bar.

10 I have also provided the machine with a releasing key which operates to release the escapement mechanism and the hesitation mechanism. The releasing key is indicated at R and consists of a lever 170 which is adapted to move the slide bar 171. The end 172 of the lever extends down through a slot 173 and is adapted to engage a projecting lug 174 on the end of this bar (see Fig. 12).

20 Said bar is provided with a laterally projecting arm 175 which extends into a vertical slot 176 in a slide plate 177 which is mounted on the inner face of the cover plate 125 (see Fig. 12). This slide bar has a slot 178 which straddles a pin 179 on the cover plate. Said slide plate 177 has an opening or cut-away portion 180 into which extends the pin 127 carried by the hesitation pawl. Said opening has a curved or cam-shaped 25 wall 181 adapted to engage said pin when the plate is moved to the right as viewed in Fig. 12, and as the pin runs by the curved or cam-shaped wall 181, the hesitation pawl will be lifted clear of the notches in the hesitation bar. The pin 182 limits the movement of the slide plate 177. The bar 171 is provided with an inclined shoulder 183 near its outer end and when the bar is moved from left to right as viewed in Fig. 12, this 30 inclined shoulder runs up on the bottom 184 of the housing in which the bar slides so that the end of the bar is raised when the bar moves from left to right. The housing is provided with a notch 185. The end of 35 the skip lifter extends through this notch and always underlies the pawl of the escapement mechanism. When the bar moves endwise and is raised through the action of this inclined shoulder, the escapement pawl is 40 raised clear of the teeth in the rack bar 25. It will thus be seen that the depression of the releasing key moving the bar 171 to the right as viewed in Fig. 12, operates to release both the feed pawl of the escapement mechanism and the pawl of the hesitation mechanism. When the carrier reaches the 45 end of its movement, through the action of the motor spring, the end 186 of the bar 171 engages the lug 187 carried by the arm 27 and this causes the bar 171 to be returned to normal position releasing both the pawl of the escapement mechanism and the pawl 50 of the hesitation mechanism.

I have provided the base plate at opposite 55 ends with spring or elastic arms 188 and 189

which engage the end of the carrier rack and serve as a cushion for stopping the movement of the carrier.

When my punch is used as a verifying punch, it is essential that the feed of the carrier at least one step, shall occur whenever the punch is depressed for verifying. Prior to my invention, so far as I am aware, no machine has been constructed wherein holes punched in the last column of a card 75 can be verified. As the carrier has reached the end of its movement the punches are brought into register with the last column of the card. I have provided means whereby the carrier may be fed a step after the holes 80 are punched or verified in the last column. The die 14 is provided with two grooves 190, 190, and the arms 36, 36 are adapted to pass through these grooves so that the carrier may be moved to the left as viewed in 85 Fig. 3, to carry the end of the card to a position entirely to the left of the die 14. When the last hole is punched, or the punch is depressed to verify the last punched hole in a card, the escapement is operated in the usual 90 way and the carrier moved to the left which indicates to the operator that the hole has been properly punched and the card is verified. This movement of the card completely 95 to the left of the die also greatly facilitates the placing of the card on the carrier and the removing of the card from the carrier. Rod 139 is secured to the base of the machine by screw 139^a and overlies the arm 139^b of the carrier end 27. The other end of rod 100 139 is held in a hole (not shown) in the stripper plate. This rod serves two purposes—it holds the card against buckling and it also guides the arms 36 into the grooves 190 of the die and stripper plate. 105

From the above it will be apparent that I have provided a machine which, as shown, is adapted for verifying the punched holes in a card such as are adapted to be used in a tabulating machine. Much of the mechanism, however, which has been described in detail may be readily used in a punch for punching the holes in cards. If holes are to be punched in cards, of course, the yielding fulcrums for the key levers will be 110 changed and fixed fulcrum points substituted therefor, and punches with cutting ends be substituted for the round end verifying punches. The manner of holding the cards in the carrier, the manner of feeding the carrier, including the skip lifter, mounting and retracting mechanism, the hesitation mechanism and the key locking mechanism are all 115 equally adapted for punching holes as well as for the punch for verifying holes, and it 120 should be distinctly understood that the inventions claimed are not restricted to use only in the verifying punch.

It is obvious that many changes may be made in the details of construction and the 130

arrangement of the parts without departing from the spirit of the invention as set forth in the appended claims.

Having thus described the invention, what I claim as new and desire to secure by Letters-Patent, is:—

1. In a machine of the class described, the combination of a series of key controlled punches, a card carrier for presenting a card to said punches, said card carrier including adjustable means engaging one end of the card whereby said card may be shifted on the carrier for registration.

2. In a machine of the class described, the combination of a series of key controlled punches, a card carrier for presenting a card to said punches, said card carrier including shiftable means engaging one end of the card whereby said card may be shifted on the carrier for registration, and a yielding member for engaging the other end of the card and holding the same against said shiftable means.

3. In a machine of the class described, the combination of a series of key controlled punches, a card carrier for presenting a card to said punches, said card carrier including adjustable arms having grooves in the ends thereof to receive one end of the card, and yielding means for engaging the other end of the card and holding the same seated in said grooves.

4. In a machine of the class described, the combination of a series of key controlled punches, a supporting base, a carrier having projecting arms overlying said base for holding the card and presenting the same to said punches, and adjustable means carried by one of said arms for engaging the end of the card.

5. In a machine of the class described, the combination of a series of key controlled punches, a supporting base, a carrier having projecting arms overlying said base for holding the card and presenting the same to said punches, and shiftable means carried by one of said arms for engaging the end of the card, said base plate having a mark thereon, said shiftable means permitting the card to be shifted to be brought into registration with said mark.

6. In a machine of the class described, the combination of a series of key controlled punches, a supporting base, a carrier having projecting arms overlying said base for holding the card and presenting the same to said punches, arms adjustably carried by one of said first-named arms for the carrier having grooves adapted to receive one end of the card, said base plate having a notch therein forming a mark, said arms being adjustable to shift the card to bring the end thereof into register with said mark.

7. In a machine of the class described, the combination of a series of key controlled

punches, a supporting base, a carrier having projecting arms overlying said base for holding the card and presenting the same to said punches, arms adjustably carried by one of said first-named arms for the carrier having grooves adapted to receive one end of the card, said base plate having a notch therein forming a mark, said arms being adjustable to shift the card to bring the end thereof into register with said mark, yielding means carried by the other arm of the carrier for engaging the other end of the card and holding the same in the groove in the adjustable arms.

8. In a machine of the class described, the combination of a series of key controlled punches, a supporting base, a carrier having projecting arms overlying said base for holding the card and presenting the same to said punches, arms adjustably carried by one of said first-named arms for the carrier having grooves adapted to receive one end of the card, said base plate having a notch therein forming a mark, said arms being adjustable to shift the card to bring the end thereof into register with said mark, a bracket carried by the other arm of the carrier and projecting downwardly into the recess in the base plate, said bracket having a notch formed therein, a yielding spring finger carried by the bracket, and projecting through said notch and engaging the other end of the card to hold said card in the grooves in the adjustable arms.

9. In a machine of the class described, the combination of a supporting base plate, a die carried thereby and extending transversely of the base plate, a series of punches associated with said die, a card carrier for moving a card across the die, said die having recesses formed therethrough, and said card carrier having projecting means adapted to pass through the recesses whereby the card may be moved by the carrier after the operation of the punching in the last column of the card.

10. In a machine of the class described, the combination of a supporting base, a die carried thereby and extending transversely of the supporting base, a series of punches associated with the die, a card carrier for moving the card over the die, said card carrier including projecting arms overlying the supporting base, an adjustable arm carried by one of the first-named arms of the carrier and adapted to engage the end of the card last operated upon by the punches, said die having a recess cut therefrom through which said card carrying arm passes whereby the card may be moved by the carrier entirely out from between the punches and die.

11. In a machine of the class described, a supporting base, a series of key controlled punches, a card carrier, a track bar extend-

- ing along said supporting base, said card carrier having rollers running on said track bar, a cover plate independent of the track bar and secured thereto for holding the rollers on the track bar.
12. In a machine of the class described, a supporting base, a series of key controlled punches, a card carrier, a track bar extending along said supporting base, said card carrier having rollers running on said track bar, a cover plate independent of the track bar and secured thereto for holding the rollers on the track bar, said cover plate being curved at its upper edge, and said rollers being mounted on pivots having projecting rounded ends extending underneath the curved upper edge of the cover plate.
13. In a machine of the class described, a supporting base, a series of key controlled punches carried thereby, a card carrier for presenting a card to said punches, and a marginal stop mechanism for initially positioning the card carrier, said marginal stop mechanism including a toothed bar carried by the supporting base, a shiftable shouldered toothed member adapted to engage the toothed bar, and means for clamping said shouldered member on said toothed bar.
14. In a machine of the class described, a supporting base, a series of key controlled punches carried thereby, a card carrier for presenting a card to said punches, and a marginal stop mechanism for initially positioning the card carrier, said marginal stop mechanism including a stop member having teeth adapted to engage the teeth of the toothed bar and lie in the path of travel of the block mounted on the card carrier, and a stirrup for clamping the stop member to the toothed bar.
15. In a machine of the class described, a supporting base, a series of key controlled punches carried thereby, a card carrier for presenting a card to said punches, a marginal stop mechanism for initially positioning the card carrier, said marginal stop mechanism including a stop member having teeth adapted to engage the teeth of the toothed bar and lie in the path of travel of the block mounted on the card carrier, a stirrup for clamping the stop member to the toothed bar, and means for locking the stirrup from endwise movement on the toothed bar and stop member.
16. In a machine of the class described, a supporting base, a die carried thereby, a series of punches, key levers for controlling the punches, and means for locking the key levers whereby only one lever can be depressed at a time, said locking means including bodily shiftable members, a chambered member in which said shiftable members are located and limiting the movement of said bodily shiftable members, and a pro-
- jecting plate carried by each key lever and adapted to pass between said bodily shiftable members and force said members to the limit of their movement.
17. In a machine of the class described, a supporting base, a die carried thereby, a series of punches, key levers for controlling the punches, and means operated by the depression of one of the punch key levers for locking all the other punch key levers so they cannot be depressed, said locking means including a tubular member having a series of slots therein, each key lever having a plate projecting through a slot in said tubular member, a series of balls in said tubular member, end blocks for limiting the movements of said balls, the diameter of the balls, being slightly less than the distance between the centers of adjacent slots, and said locking plates being of sufficient thickness to move the balls to the limit of their movements, whereby when one locking plate is between two of the balls and the key lever depressed said balls will prevent the depression of any other key lever.
18. In a machine of the class described, a shiftable card carrier, a rack bar for controlling the movements of the card carrier, said rack bar having gear teeth formed therein, a ratchet gear mounted on the card carrier and engaging the gear teeth in the rack bar, a spring for rotating said ratchet gear, common means on which the ratchet gear and spring are mounted whereby said spring and gear may be bodily shifted to bring the gear out of engagement with the teeth in the rack bar to permit the changing of the tension on the spring.
19. In a machine of the class described, a shiftable card carrier, a rack bar for controlling the movements of the card carrier, said rack bar having gear teeth formed therein, a ratchet gear mounted on the card carrier and engaging the gear teeth in the rack bar, a spring for rotating said ratchet gear, a plate, a pivot pin carried by the plate on which said ratchet gear is mounted, a spring encircling the ratchet gear and connected at one end to said ratchet gear and at its other end to said plate, means for holding the ratchet gear on its pivot pin, and means whereby said supporting plate may be shifted to cause said gear to be unmeshed from the gear teeth on the rack bar to permit the changing of the tension on the spring.
20. In a machine of the class described, the combination of a series of key controlled punches, a card carrier for presenting a card to said punches, an escapement mechanism for shifting a card relative to the punches, a skipping mechanism for causing the card carrier to skip from one field of operation to another including a skip lifter, a spring toggle mechanism for holding said skip lift-

- er in retracted or extended position, a pivot pin fixedly secured to said toggle mechanism and adapted to pass through a hole in the end of the skip lifter, and sliding means 5 extending over the top of said pivot pin for retaining the skip lifter on said pivot pin.
21. In a machine of the class described, the combination of a series of key controlled punches, a card carrier for presenting a card to said punches, an escapement mechanism for shifting a card relative to the punches, a skipping mechanism for causing the card carrier to skip from one field of operation to another including a skip lifter, a spring 10 toggle mechanism for holding said skip lifter in retracted or extended position, a pivot pin fixedly secured to said toggle mechanism and adapted to pass through a hole in the end of the skip lifter, and a sliding bolt adapted to extend over the top of said pivot pin for retaining the skip lifter thereon.
22. In a machine of the class described, the combination of a series of key controlled punches, a card carrier for presenting a card to said punches, an escapement mechanism for shifting a card relative to the punches, a skipping mechanism for causing the card carrier to skip from one field of operation to another including a skip lifter, a spring 15 toggle mechanism for holding said skip lifter in retracted or extended position, a pivot pin fixedly secured to said toggle mechanism and adapted to pass through a hole in the end of the skip lifter, a sliding plate adapted to extend over the top of said pivot pin for retaining the skip lifter thereon, and a screw for locking said plate in position over said pivot pin.
23. In a machine of the class described, the combination of a series of key controlled punches, a card carrier for presenting a card to said punches, an escapement mechanism for shifting a card relative to the punches, a skipping mechanism for causing the card carrier to skip from one field of operation to another including a skip lifter, a spring 20 toggle mechanism for holding said skip lifter in retracted or extended position, a pivot pin fixedly secured to said toggle mechanism and adapted to pass through a hole in the end of the skip lifter, a sliding plate adapted to extend over the top of said pivot pin for retaining the skip lifter thereon, and a screw for locking said plate in position over said pivot pin.
24. In a machine of the class described, the combination of a series of key controlled punches, a card carrier for presenting a card to said punches, an escapement mechanism for shifting a card relative to the punches, a skipping mechanism for causing the card carrier to skip from one field of operation to another including a skip lifter, a spring 25 toggle mechanism for holding said skip lifter in retracted or extended position, a pivot pin fixedly secured to said toggle mechanism and adapted to pass through a hole in the end of the skip lifter, a sliding plate adapted to extend over the top of said pivot pin for retaining the skip lifter thereon, and a screw for locking said plate in position over said pivot pin.
25. In a machine of the class described, the combination with a series of key controlled punches, of a card carrier for presenting a card to said punches, an escapement mechanism for feeding the card carrier, and a skipping mechanism for causing the card carrier to skip from one field of operation to another, said skipping mechanism including a skip lifter, and spring toggle mechanism for holding said skip lifter in retracted or extended position, and means 30 operated by the card carrier on the first part of its movement to position for punching for retracting the skip lifter.
26. In a machine of the class described, the combination with a series of key controlled punches, of a card carrier for presenting a card to said punches, an escapement mechanism for feeding the card carrier, and a skipping mechanism for causing the card carrier to skip from one field of operation to another, said skipping mechanism including a skip lifter, and spring toggle mechanism for holding said skip lifter in retracted or extended position, a retractor arm for engaging the toggle mechanism for 35 retracting the skip lifter, yielding means for holding said arm in an intermediate position, and means whereby said carrier shifts the arm on the initial part of its movement to punching position for swing- 40 ing the arm to retract the skip lifter.
27. In a machine of the class described, the combination with a series of key controlled punches, of a card carrier for presenting a card to said punches, an escapement mechanism for feeding the card carrier, and a skipping mechanism for causing the card carrier to skip from one field of operation to another, said skipping mechanism including a skip lifter, and spring 45 toggle mechanism for holding said skip lifter in retracted or extended position, a pivoted retractor arm having an inclined ledge, a shoulder on said arm adapted to engage the toggle mechanism for retracting 50

the skip lifter, swinging arms, a spring and stops associated therewith for yieldingly holding said retractor arm in intermediate position, and a pin mounted on the carrier and adapted to engage said ledge for swinging the retractor arm to retract the skip lifter on the initial movement of the carrier toward punching position.

28. In a machine of the class described, a series of key controlled punches, a card carrier for presenting a card to said punches, an escapement mechanism for feeding the card carrier step by step, and a hesitation mechanism controlled by the keys for causing the card carrier to remain with a given field in the card beneath the punches for the predetermined number of key depressions.

29. In a machine of the class described, the combination of a supporting base, a die bar extending across said base, a series of punches arranged in the line of the die bar, key controlled levers for actuating said punches, a card carrier for moving a card transversely across the die and beneath the punches, an escapement mechanism for moving the card carrier step by step, and a hesitation mechanism controlled by the key levers for causing the card carrier to remain unmoved with a given field in a card directly beneath the punches for a predetermined number of key depressions.

30. In a machine of the class described, the combination of a supporting base, a series of key controlled punches, a card carrier for presenting the card to said punches, an escapement mechanism for feeding the card carrier step by step, and a hesitation mechanism including a hesitation bar having notches formed therein corresponding to the fields where the series of holes in the same vertical column are to be punched or verified, a pawl adapted to engage said notch, means operated by the keys for lifting said pawl one step from said notch for each hole punched in the same vertical column whereby the depth of the notch determines the number of holes punched or verified in the vertical column before the advance movement of the card carrier.

31. In a machine of the class described, the combination of a series of key controlled punches, a card carrier for presenting the cards to said punches, an escapement mechanism for feeding the card carrier step by step, and a hesitation mechanism including a hesitation bar having notches therein corresponding with the field in the card where it is desired to punch or verify the series of holes in a vertical column, a hesitation pawl adapted to cooperate with said hesitation bar, said pawl having a slot formed therein, a pivot pin extending through said slot, a spring for moving the pawl endwise on said pivot pin, said hesi-

tation pawl having a segment rack at the rear end thereof, a feed pawl for said rack normally out of engagement therewith, means operated by the keys for moving the feed pawl for causing the same to lift the hesitation pawl step by step out of a notch in the hesitation bar, a locking dog associated with said feed pawl, said hesitation pawl being moved rearwardly when engaged by the notch in the hesitation bar to bring the segment rack carried thereby into operative engagement with the feed pawl.

32. In a machine of the class described, the combination of a series of key controlled punches, a card carrier for presenting the cards to said punches, an escapement mechanism for feeding the card carrier step by step, and a hesitation mechanism including a hesitation bar having notches therein corresponding with the field in the card where it is desired to punch or verify the series of holes in a vertical column, a hesitation pawl adapted to cooperate with said hesitation bar, said pawl having a slot formed therein, a pivot pin extending through said slot, a spring for moving the pawl endwise on said pivot pin, said hesitation pawl having a segment rack at the rear end thereof, a feed pawl for said rack normally out of engagement therewith, means operated by the keys for moving the feed pawl for causing the same to lift the hesitation pawl step by step out of a notch in the hesitation bar, a locking dog associated with said feed pawl, said hesitation pawl being moved rearwardly when engaged by the notch in the hesitation bar to bring the segment rack carried thereby into operative engagement with the feed pawl.

33. In a machine of the class described, a series of key controlled punches, a card carrier for presenting a card to said punches, an escapement mechanism for feeding the card carrier step by step, a hesitation mechanism for controlling the movement of the card carrier whereby a series of key operations are required before the card carrier is moved forward, and a releasing mechanism for releasing the escapement mechanism and the hesitation mechanism.

34. In a machine of the class described, the combination of a series of key controlled punches, a card carrier for presenting a card to said punches, an escapement mechanism for feeding the card carrier step by step and including an escapement pawl, a rack bar associated with said escapement pawl, a hesitation mechanism for causing the carrier to remain in a given position for a series of key depressions including a hesitation pawl, a hesitation bar with which said pawl is associated, a releasing key, and

devices operated thereby for lifting the escapement pawl free of the rack bar and the hesitation pawl free of the hesitation bar.

35. In a machine of the class described, the combination of a series of key controlled punches, a card carrier for presenting a card to said punches, an escapement mechanism for feeding the card carrier step by step and including an escapement pawl, 10 a rack bar associated with said escapement pawl, a hesitation mechanism for causing the carrier to remain in a given position for a series of key depressions including a hesitation pawl, a hesitation bar with 15 which said pawl is associated, a skipping mechanism including a skip lifter projecting beneath the escapement pawl, a releasing key, a sliding bar operated by said releasing key for lifting the skip lifter to 20 raise the escapement pawl from engagement with the rack bar, and a sliding plate operated by said sliding bar and having a cam surface for raising the hesitation pawl from engagement with the hesitation bar.

25. 36. In a machine of the class described, the combination of a series of key controlled punches, a card carrier for presenting the card to said punches, a rack bar, a motor spring for moving the card carrier 30 along the rack bar, an escapement mechanism associated with said rack bar and including an escapement pawl, means for 35 yieldingly mounting said escapement pawl whereby the movements of the carrier into engagement with said pawl are cushioned.

37. In a machine of the class described, the combination of a series of key controlled punches, a card carrier for presenting the card to said punches, a rack bar, a 40 motor spring for moving the card carrier along the rack bar, an escapement mechanism associated with said rack bar and in-

cluding an escapement pawl, a swinging member carrying said escapement pawl, a spring for moving the escapement pawl in a direction opposed to the feed movements of the carrier, and a stop for determining the position of said escapement pawl. 45

38. In a machine of the class described, the combination of a series of key controlled punches, a card carrier for presenting the card to said punches, a rack bar, a motor spring, for moving the card carrier along the rack bar, an escapement mechanism associated with said rack bar and including 50 an escapement pawl, a swinging member on which said escapement pawl is carried, a flat spring connected to said swinging member, and means for putting said flat spring under tension for turning 55 the swinging member to move the pawl in a direction opposed to the feed movements of the carrier.

39. In a machine of the class described, the combination of a series of key controlled punches, a card carrier for presenting a card to said punches, a rack bar, a motor spring for moving the card carrier along the rack bar, an escapement mechanism associated with said rack bar and including an escapement pawl, a swinging member on which 65 said escapement pawl is carried, a flat spring connected to said swinging member, means for putting said flat spring under tension for turning 70 the swinging member to move the pawl in a direction opposed to the feed movements of the carrier, and an adjustable stop screw for engaging said swinging member for determining the position of the escapement pawl. 75

In testimony whereof, I affix my signature.

JOHN T. SCHAAFF.
